The ornamental design for a vibrator hand for an alarm clock, as shown and described.

DESCRIPTION

FIG. 1 is a front elevational view of a vibrator hand for an alarm clock showing my new ornamental design with the cord broken away to indicate indeterminate length;
FIG. 2 is a top plan view thereof;
FIG. 3 is a bottom plan view thereof;
FIG. 4 is a rear elevational view thereof;
FIG. 5 is a left side elevational view thereof; and,
FIG. 6 is a right side elevational view thereof.
